FILE DRAWER

Frank D. Jonas, Upper Brookville, and Edward D. Patterson, Sea Cliff, N. Y., assignors to Oxford Filing Supply Co., Inc., Garden City, N. Y., a corporation of New Jersey

Application November 19, 1953, Serial No. 393,157

12 Claims. (Cl. 229—30)

The present invention relates to drawer structures and particularly to file drawers.

More particularly still the invention relates to a file drawer constructed of corrugated paper board or the like which may be shipped in an opened-out flat condition and readily erected into the usual drawer structure.

It is an object of the invention to provide a drawer which is formed primarily of corrugated paper board and which is so organized that it may be shipped in an opened-out flat condition and may be readily assembled into the drawer form by the user without special tools.

It is another object of the invention to provide such a drawer wherein means are provided for locking the upstanding sides into position which means are readily unlatched without the use of special tools so that the drawer may be again opened into a flat condition either for storage or for further shipment.

It is a further object of the invention to provide such a drawer structure having a metal-clad front and provided with the usual handle and place for a label or card intended to identify the drawer contents.

Other objects and features of the invention will be apparent when the following description is considered in connection with the annexed drawings, in which,

Figure 1 is a perspective view of the assembled drawer, the view likewise showing in dotted lines the appearance of the structure when the left hand side wall has been folded into the plane of the base;

Figure 2 is a top plan view of the drawer in its flat condition prior to erection into the completed form;

Figure 3 is a vertical cross-section of the structure of Figure 2, the section being taken on the plane of the line 3—3 of Figure 2;

Figure 4 is a top plan view of the paper board blank with the locking elements in place but prior to the folding of the various elements of the blank to form the final drawer structure;

Figure 5 is a cross-sectional view of the blank of Figure 4, the view being taken on the plane of the line 5—5 of Figure 4;

Figure 6 is a fragmentary view of the mating locking members, one of which is located on a side wall and the other on the end wall of the drawer. This view shows the members in the positions which they assume when the drawer has been assembled and illustrates particularly the mode of locking the drawer walls into their erected position;

Figure 7 is a horizontal cross-sectional view showing the construction of the front wall of the drawer, the view being taken on the plane of the line 7—7 of Figure 1; and

Figure 8 is an enlarged view of the left-hand forward corner of the drawer structure showing the mode of locking a side wall to the front wall, the view being taken on the plane of the line 8—8 of Figure 1.

Referring now to the drawings, there is shown in Figure 1 a completed file drawer in accordance with the in-

2

vention, the drawer comprising a base 10, side walls 11 and 12, a rear wall 13 and a front 14.

Referring now to Figure 4, it will be seen that the side wall 11 is provided with the score lines 15 and 16 and the side wall portion 11 of the blank is separated from the base 10 by an additional score line 17. In like manner, side wall portion 12 of the blank is provided with score lines 18 and 20 and is separated from the base portion by the score line 21. The front wall portion 14 of the box blank is provided with the score lines 22, 23, 24 and 25 and is separated from the base portion of the blank by the score line 26. It should be noted that score lines 23 and 24 are parallel to and slightly offset from the score lines 17 and 21 respectively.

In a similar manner the rear wall portion of the blank is provided with the score lines 27, 28, 30 and 31 and with a further score line 32 which separates the rear wall portion of the blank from the base 10. Additionally, the rear wall portion 13 is provided with a flap 33, the blank being scored along the line 34 separating the flap from the main rear wall portion 13. Here again it should be noted that the score lines 28 and 30 are parallel to and slightly apart from the score lines 17 and 21.

With the blank opened out and in the condition shown in Figure 4, the latching elements designated 35 and 36 are positioned as shown in the drawing, an element 35 being placed at each end of each of the side walls 11 and 12 and an element 36 being placed adjacent the score lines 23, 24, 28 and 30 on the front and rear walls 13 and 14.

Referring now to Figure 6 it will be seen that each locking element 35 comprises a plate-like member 37 having an extending tongue 38 formed thereon and offset from the plane of the plate 37, the tongue terminating in a notched portion 40. Additionally, the element 35 at its opposite end is provided with a portion 41 offset from the plane of the plate in the direction opposite to the offsetting of the tongue 38. The peculiar configuration of the plate 37 shown in the drawings results from the fact that these plates are stamped from a continuous strip. It will of course be clear that the elements 35 are of two types differing only in that the tongue of one type is offset in a direction opposite to the tongues of the second type.

The mating locking element 36 is likewise formed from sheet metal and comprises a plate having a notch 42 on one edge thereof, the material being bent first forwardly, then parallel to the main body of the material, then again rearwardly forming the channel-shaped member 43, this member having a bar 44 extending in a vertical direction at the rear of the element 36. The channel member 43 is provided with an opening 45 at its left hand edge, as seen in Figure 6, this opening being composed of a wider entrance portion and a narrower terminating portion lying adjacent the right hand vertical wall of the channel 43. Additionally, the material from which the element 36 is formed is punched out to form a latching tongue 46 which is bent out of the plane of the element 36 in a forward direction.

It will be seen from the above and by reference to Figure 6 that the tongue 38 may be inserted in the wider entrance opening of the cutout portion 44 of the channel 42 with the notches in the portion 40 of member 35 lying in the plane of the forward wall of the channel 43 and then moved to the right as seen in Figure 6 until the opposing portions of the opening in wall 43 lie in the notches of a portion 40 of tongue 38. At this time the tongue 46 of the member 36 will have been pressed toward the rear by the tongue 38 of member 35 and will have sprung forwardly to lie in the path of movement of the tongue 38 and prevent disengagement of tongue 38 from the mating opening in the forward wall of channel 43.

Referring now again to Figure 4, it will be seen that the outermost portion of each of the side walls 11 and 12

is provided with a pair of slits all of which are designated 47. These slits are so located as to fit over the upstanding portions 41 of the locking members 35 when the locking members are positioned as indicated in Figure 4 with their tongues extending beyond the edges of the side walls 11 and 12 and with their corresponding edges in alignment with the forward and rearward edges of the side walls 11 and 12. When the locking members 35 have been thus positioned the blank is folded inwardly along the score lines 15 and 18 and glued and then again folded inwardly along the score lines 16 and 20 and again glued, resulting in the side walls appearing as shown in Figure 2. It should be noted that the bent off portions 41 of locking members 35 are provided with small teats 48 extending beyond the edge of the portions 41. Thus when the outermost flaps are bent inwardly along the lines 15 and 18 the portions 41 lie substantially completely within the slots 47, that is, portions 41 are of substantially the same thickness as the paper board of which the drawer is formed. Portions 48, however, extend beyond the paper board and when the subsequent fold is made these portions penetrate into the material of the innermost flap, thus also contributing to holding the locking elements 35 in their proper positions.

The outer sections of the front and rear wall portions 13 and 14 are in a similar manner provided with slits all of which are designated 50, which slits are positioned to overlie the vertical extensions 44 of the latching or locking elements 36. Locking elements 36 are located as indicated particularly in Figure 4, small rectangular portions of the material being cutout to provide for the insertion of the channel members 43 which channel members have a depth substantially equal to the thickness of the paper board material. When the locking members have been located as above indicated, the outer flaps are folded inwardly along the core lines 22, 25, 27 and 31 placing the respective slits 50 over the bars 44 of the associated locking members, and the material glued. Thereafter, the material is again folded inwardly along the lines 23, 24, 28 and 30. Next the flap 33 of the rear wall 13 is folded along the score line 34 and in the position shown in Figure 3. As a further step a front 51, which may conveniently be of sheet metal having turned upper and side edges as indicated at 52 and 53 (Figure 1) is placed over the front 14 and held in place by a U-shaped member 54 having brad-like extensions 55 thereon which brad-like extensions pass through the folded paper board structure and through a strap 56 and are then bent over to hold the metal facing 51 and the U-shaped member 54 in place. It should be noted that the U-shaped member 54 is inserted about a portion of a handle 57 so that it serves both to hold the metal facing 51 in place and to also hold the handle in position.

The structure as heretofore described and as shown in Figure 3 is completed and it is intended that it be forwarded in this condition to the user. At the point of use the side walls are folded upwardly along the score lines 17 and 21 and the front and rear walls likewise folded upwardly along the score lines 26 and 32. With the walls in this upstanding condition the side walls may be moved inwardly slightly beyond the vertical position thereby aligning the tongues 38 with the openings 45 in the channels 43, after which a movement of the side walls to the exact vertical position will cause engagement of the notches of the portion 40 of tongues 38 with a narrow terminating portion of the openings 45 of the channels 43 so that the side walls are locked to the front and rear walls, it being understood that the tongues 46 will snap into place and it will prevent movement of the side walls in any direction as well as movement of the front and rear walls. In brief, a rigid unitary drawer structure will be formed by the action of the locking members 35 and 36.

When the structure has been erected in the manner above-described, the protruding tongues 38 of the latch

members 35 are completely hidden and only a small portion of the mating latch members 36 is visible. Furthermore, due to the multi-folded condition of the paper board from which the drawer is made, the structure is rigid and has considerable strength. Additionally, due to the use of the metal front piece the drawer is identical in appearance with the drawers commonly utilized and which are fabricated entirely of metal. The metal front 51 may be provided with slits, such as shown at 60 in Figure 1, through which the corners of an identifying label or tag may be inserted, this tag of course bearing an indication of the contents of the particular file drawer.

While we have described a preferred embodiment of the invention, it will be understood that we wish to be limited not by the foregoing description, but solely by the claims granted to us.

What is claimed is:

1. In a file drawer structure, in combination, a base and side, front and rear walls each formed of plural thicknesses of paper board, the side walls having latching members at each end thereof, said latching members having tongues protruding beyond the ends of said side walls, the remainder of said members being enclosed between the thicknesses of said paper board, apertured latching members facing inwardly and located adjacent the side edges of said front and rear walls, said apertured latching members being held between thicknesses of said paper board, apertured portions of said mating members lying substantially flush with the inner surface of the inner thickness of said paper board, said portions cooperating with said tongues of said first mentioned members to lock said side, front and rear walls in upstanding position and means for locking said tongues in said apertured latching members.

2. A drawer as claimed in claim 1, characterized in that said first mentioned latching members comprise plates and said tongues are notched and further characterized in that said second-mentioned latching members are provided with opposed wall portions adapted to enter the notches in the tongues of said first-mentioned latching members.

3. A drawer as claimed in claim 2, characterized in that said first-mentioned latching members each comprise a plate having a tongue formed integrally therewith, said plates each having a portion thereof bent over at right angles to the plane thereof to form a projection, and further characterized in that one thickness of said paper board is provided with a slit into which said projection extends to fix said latching member in position in its associated side wall.

4. A drawer structure as claimed in claim 2, characterized in that each of said second-mentioned latching members comprises a plate having a vertically extending channel bent therefrom, said channel having an opening in one side wall and the front thereof, said opening being adapted to receive said notched tongue of the cooperating first-mentioned latching member.

5. A drawer structure as claimed in claim 4, further characterized in that each of said second-mentioned latching members has a finger portion stamped therefrom, said finger extending perpendicularly to said channel, the end of said finger lying adjacent the tongue of the cooperating first-mentioned latching member, said finger serving to hold said first-mentioned tongue in position in said opening of said second-mentioned latching member.

6. A drawer structure as claimed in claim 4, characterized in that each said channel member is of substantially the same thickness as said paper board material, said channel being inserted in an opening cut in one thickness of said material, the body portion of each said latching member being positioned between the thicknesses of the front or rear wall and the face of said channel being flush with the inner surface of the corresponding front or rear wall.

7. In a drawer structure, in combination, a base, side

walls and rear walls, means for holding said walls in position at right angles to the plane of said base, said means comprising separable pairs of positively locking latching members enclosed between folded-over portions of the material of which said base, side and end walls, are formed, said side walls comprising a lower portion of a single thickness of material and an upper portion having three thicknesses of material, said material being glued together after folding, said latching members moving into positive locking position in a direction at right angles to the planes of the side walls.

8. In a drawer structure, in combination, a base, side walls and rear walls, means for holding said walls in position at right angles to the plane of said base, said means comprising latching members all of which are enclosed between folded-over portions of the material of which said base, side and end walls, are formed, said front and rear walls comprising three thicknesses of material, and being formed by folding a blank section of substantially three times the width of the drawer inwardly along score lines extending perpendicularly to the drawer base, said score lines being positioned at each edge of said front and rear walls and at points spaced outwardly from said first-mentioned score line a distance equal to half the drawer width, said portions being glued after folding.

9. A drawer structure as claimed in claim 8, characterized in that latching members are inserted adjacent the score lines defining the width of the drawer, said latching members having projections extending outwardly from the plane thereof, and further characterized in that the outermost edges of the rear and front wall blanks are provided with slits, said slits being adapted to engage

said projections when said folding is performed, to thereby lock said latching members in place between the thicknesses of said front and rear walls.

10. A knock-down drawer comprising a single sheet of fibrous material folded upon a multiple of score lines to form plural layer side and end walls, each side wall having a plate at each free corner secured between the layers forming the wall, each such plate having a latching tongue consisting of an enlarged head joined to the plate with a narrow neck, and each end wall having a plate at each side secured between the layers forming the wall, each such plate having an aperture consisting of a large portion and a communicating narrow portion, the head of each tongue passing through the large portion of the aperture of the associated plate and movable at right angles to the plane of the tongue so that its neck lies in the narrow portion of the aperture in a locked position when the drawer is set up.

11. In the combination of claim 10, a locking finger for holding each tongue in locked position.

12. In the combination of claim 10, a locking finger for holding each tongue in locked position, each tongue comprising a resilient cantilever integral with the associated plate.
